UNITED STATES PATENT OFFICE.

CHARLES STOLLBERG, OF TOLEDO, OHIO, ASSIGNOR TO AMERICAN CAN COMPANY, A CORPORATION OF NEW JERSEY.

BAILED SHEET-METAL KEG FOR WHITE LEAD OR OTHER HEAVY MATERIALS.

No. 853,882.

Specification of Letters Patent.

Patented May 14, 1907.

Application filed April 7, 1906. Serial No. 310,575.

To all whom it may concern:

Be it known that I, CHARLES STOLLBERG, a citizen of the United States, residing in Toledo, in the county of Lucas and State of Ohio, have invented a new and useful Improvement in Bailed Sheet-Metal Kegs for White Lead or other Heavy Materials, of which the following is a specification.

My invention relates to improvements in the construction of sheet metal kegs or vessels for holding and shipment of white lead or other heavy materials.

My invention consists in a sheet metal keg having a seamless, or preferably seamless, body drawn up out of one piece with integral bottom, and having an open mouth at its upper end of full size, adapted to receive an inside tight fitting friction cover and provided with an outwardly curled edge or roll at its upper end, embracing a strengthening and stiffening wire, and provided with integral cover holding lips adapted to be pinched or bent down over the rim of the cover after the cover has been inserted, the strengthening wire having at diametrically opposite points integral coils therein forming bail ears or eyes to receive the hooks of the bail, a bail secured to said bail ears, and an inside tight fitting friction cover fitting within the open mouth of the body of the keg and serving to stiffen and strengthen the upper end thereof, as well as to close the package.

My invention also consists in the novel construction of parts and devices, and in the novel combination of parts and devices herein shown and described.

In the accompanying drawing forming a part of this specification, Figure 1 is a central vertical section of a sheet steel keg for white lead or other like materials, embodying my invention. Fig. 2 is a horizontal section on line 2—2 of Fig. 1. Fig. 3 is a detail partial plan view showing the bail in section, and Fig. 4 is a detail elevation showing one of the bail ears and a portion of the bail.

In the drawing, A represents the seamless body of my sheet steel keg, the same having an integral bottom or lower head A¹ and an integral roll or curl a at its upper edge embracing a strengthening wire B which fits within the annular roll a and is thus firmly and securely united to the body of the vessel. The strengthening wire B has integral loops

or coils b at diametrically opposite points of the keg to form bail ears or eyes b for receiving the hooks c of the wire bail C. The flange a¹ forming the curl or roll a has integral upwardly projecting lips a² at the upright or transversely extending integral bail ear coils b, which lips are adapted to be bent down over the rim of the cover D after the cover is inserted. The cover holding lips a² form slots or open segments in the roll a to receive and accommodate the bail car coils or loops d of the wire B.

The cover D has an upwardly projecting friction seat wall or flange d terminating in a horizontally projecting flange or shoulder d¹, the friction seat wall or flange d fitting snugly within the mouth a³ of the body A and forming a tight frictional fit therewith and thus effecting a secure closure of the keg and at the same time, bracing, stiffening and strengthening the upper or mouth end thereof. After the keg has been filled, and the cover driven or forced home, the integral cover holding lips a² are clenched or bent down over the rim of the cover, thus securely locking it in place. As the bail ears b are integral with the wire B and as this wire B, embracing the upper end of the body, is itself snugly embraced within the annular roll a at the upper end of the body of the keg, the bail ears are very firmly and securely attached, and at the same time of a very simple construction adding little to the cost of the vessel as a whole. The strengthening wire B may, if desired, be made in two separate pieces as indicated by the dotted lines b¹ in Fig. 2 of the drawing.

I claim:

1. The sheet steel keg for white lead or other materials, comprising a seamless body, an integral bottom, the body having an integral roll at its upper end, a strengthening wire surrounding the body and embraced within said roll and provided with diametrically opposite integral bail ear coils, a tight friction fit cover fitting within the mouth of the body, said body having integral cover holding lips bent down over the rim of the cover to lock the cover in place, and a bail, substantially as specified.

2. The sheet steel keg for white lead or other materials, comprising a seamless body, an integral bottom, the body having an inte-

gral roll at its upper end, a strengthening wire surrounding the body and embraced within said roll and provided with diamet-
5 rically opposite integral bail ear coils, a tight friction fit cover fitting within the mouth of the body, said body having integral cover holding lips bent down over the rim of the cover to lock the cover in place, said cover having a projecting marginal flange fitting 10 against the said roll on the upper end of the body, substantially as specified.

3. A sheet metal vessel having a body furnished with an integral roll at its upper edge, a strengthening wire embraced thereby and 15 provided with integral bail ear coils or loops and a cover fitting within the mouth of said body and said body having integral cover holding lips at said bail ear coils or loops, said cover holding lips forming slots or openings

in said roll to receive said bail ear coils or 20 loops, substantially as specified.

4. In a sheet metal vessel, the combina-
25 tion with a body having a strengthening wire at its upper end and a flange embracing said wire, said wire being provided with integral bail ears or loops, a cover fitting within the mouth of said body and cover holding lips on the body, adjacent to said bail ears or loops, said cover holding lips being integral with said wire embracing flange of the body and 30 forming slots or openings therein to receive said bail ears or loops, substantially as specified.

CHARLES STOLLBERG.
